UNITED STATES PATENT OFFICE.

EDGAR A. NATHAN, OF NEW YORK, N. Y.

DESIGN FOR A COMBINED ASH TRAY AND CIGAR, PIPE, AND MATCH HOLDER.

Application filed April 8, 1926. Serial No. 17,219. Term of patent 14 years.

To all whom it may concern:

Be it known that I, EDGAR A. NATHAN, a citizen of the United States, residing at 161 West 86th Street, in the city of New York, county of New York, and State of New York, have invented a new, original, and ornamental Design for a Combined Ash Tray and Cigar, Pipe, and Match Holder, of which the following is a specification, reference being had to the accompanying drawing, forming part thereof.

The figure is a view in perspective of a combined ash tray and cigar, pipe, and match holder, showing my new design.

I claim:

The ornamental design for a combined ash tray and cigar, pipe, and match holder, as shown.

EDGAR A. NATHAN.
